UNITED STATES PATENT OFFICE.

GEORGE B. THOMAS, OF BRIDGEPORT, CONNECTICUT, ASSIGNOR TO PERKINS ELECTRIC SWITCH MANUFACTURING COMPANY, OF BRIDGEPORT, CONNECTICUT, A CORPORATION OF CONNECTICUT.

PENDENT ELECTRIC SWITCH.

No. 926,622.

Specification of Letters Patent.

Patented June 29, 1909.

Application filed March 28, 1906. Serial No. 307,665.

To all whom it may concern:

Be it known that I, GEORGE B. THOMAS, a citizen of the United States of America, residing in Bridgeport, county of Fairfield, and 5 State of Connecticut, have invented certain new and useful Improvements in Pendent Electric Switches, of which the following is a specification.

It is the object of my invention to construct a simple, inexpensive and efficient pendent electric switch.

In the accompanying drawings Figure 1 represents a plan view, drawn to an enlarged scale, of the switch with the shell removed; 15 Fig. 2 is a central vertical section of the casing on the line 2—2, Fig. 1; Fig. 3 is a section on the line 3—3, Fig. 1; and Fig. 4 is a side view of the complete switch.

Referring to these drawings, 11 is a cup-shaped body or casing of porcelain or other insulating material, of a single piece. This insulating body completely incloses the switch operating mechanism, being open at the top for the insertion of the switch mechanism and closed at the bottom, except where holes 30 are provided for the free passage of the two push buttons 12 and 13 and for securing screws, as will be hereinafter described.

30 On the top surface of the insulating body, are secured terminal plates 15, by means of the screws 19 and 20 passing longitudinally through the casing. These plates carry binding posts 16 for the incoming wires and 35 are in electrical connection with the spring contact plates 17 and 18. The contact plates 17 and 18 project down into the interior of the porcelain body to coöperate with the contact lever 22 of the switch mechanism.

40 The switch operating mechanism proper, comprising a rock shaft 21 and the make and break contact lever 22, and other necessary parts may be substantially such a snap switch as is shown in my prior patent No. 743,348, November 3, 1903. This mechanism is carried on a supporting plate 23, mounted on one side of the interior of the casing and held by suitable horizontal screws 45 24 (Fig. 2), passing through one side of the insulating body. Over the top of the casing is placed a plate or sheet of insulation 28 (Fig. 3) between the screws of the binding

posts and the switch to prevent the loose ends of the terminal wires from making a short circuit.

The operation of the mechanism is substantially the same as that of my above mentioned patent. By pressing the lower of the two push buttons, the rock shaft 21 60 tensions the spring until the catch is released, when the contact 22 swings over, either making or breaking the circuit through the spring clips 17 and 18. In the drawing the switch lever is shown as thrown 65 over to the open position.

The parts described are inclosed by a metallic casing 10, Fig. 4, the wires coming in through the usual ferrule 14.

I claim as my invention—

70 1. A push button pendent switch, comprising an outer casing and an insulating cup-shaped body open at the top for the insertion of the switch mechanism, in combination with binding posts and spring clips at 75 the top thereof, switch mechanism inclosed in the body and a sheet of insulation separating the binding posts from the switch mechanism.

2. A push button pendent switch, comprising a one-piece cup-shaped porcelain body open at the top for the insertion of the switch mechanism, in combination with switch mechanism wholly contained within the insulating body, a supporting plate for 85 the switch mechanism, securing screws for the said plate passing through the side wall of the insulating body, and the two push buttons passing through holes in the bottom of said body.

90 3. A two-button pendent switch comprising a body of insulation having a longitudinal slot, extending therethrough, contact fingers at one end of said slot near one side of said body, and a bridging switch-blade pivoted near the other end of said slot and adapted to swing in said slot transversely of said body.

95 In testimony whereof I have signed my name to this specification, in the presence of 100 two subscribing witnesses.

GEORGE B. THOMAS.
